US0D1043316S

(12) **United States Design Patent** (10) Patent No.: **US D1,043,316 S**
(45) Date of Patent: ** Sep. 24, 2024

(54) **LOCK**

(71) Applicant: **Ningbo Eudemon Child Protective Equipment Co., Ltd.**, Ningbo (CN)

(72) Inventors: **Binhui Li**, Zhejiang (CN); **Zhen Zhang**, Zhejiang (CN)

(**) Term: **15 Years**

(21) Appl. No.: **35/519,122**

(22) Filed: **Sep. 22, 2023**

(80) **Hague Agreement Data**

Int. Filing Date: **Sep. 22, 2023**

Int. Reg. No.: **DM/233197**

Int. Reg. Date: **Sep. 22, 2023**

Int. Reg. Pub. Date: **Nov. 24, 2023**

(30) **Foreign Application Priority Data**

May 24, 2023 (CN) 202330310198.3
Aug. 15, 2023 (CN) 202330520355.3

Primary Examiner — Garth Rademaker

Assistant Examiner — Christina Gabrielle Cosden

(57) **CLAIM**

The ornamental design for lock, as shown and described.

DESCRIPTION

1. Lock

1.1 : Front

1.2 : Back

1.3 : Left

1.4 : Right

1.5 : Top

1.6 : Perspective

1.7 : Exploded

1.8 : Perspective
